UNITED STATES PATENT OFFICE.

CHARLES H. ANGUS, OF EAST HAVEN, CONNECTICUT.

ADJUSTABLE ROLL-CURTAIN FIXTURE.

1,303,010.

Specification of Letters Patent.

Patented May 6, 1919.

Application filed June 8, 1918. Serial No. 238,931.

To all whom it may concern:

Be it known that I, CHARLES H. ANGUS, a citizen of the United States, residing at East Haven, in the county of New Haven and State of Connecticut, have invented new and useful Improvements in Adjustable Roll-Curtain Fixtures, of which the following is a specification.

This invention relates to improvements in curtain fixtures and aims to provide a curtain supporting bracket which is capable of adjustment after being attached to the window frame for the purpose of accommodating curtains of different widths.

15 To this end the invention includes a plate adapted to be attached upon the window frame and provided with longitudinal flanges spaced from its front face along each edge thereof to define grooves for the reception of an engaging foot carried by the bracket arm and oppositely extending slots formed in said arm for receiving the longitudinal flanges.

20 The invention also includes novel means for locking the bracket arm at any point throughout the length of the plate, the said means comprising a locking plate pivotally secured to the bracket arm and carrying a blade at one end for engagement with serrations formed in the front face of the edging plate, aligned finger pieces carried by the bracket arm and locking the plate respectively and a spring interposed between the finger pieces to normally hold the engaging 25 blade in contact with the serrated face of the edging plate.

In the drawings:—

Figure 1 is a horizontal sectional view through a portion of a window casing with 30 the invention applied thereto, the edging plate being shown in section and the remainder of the invention in plan;

Fig. 2 is a vertical sectional view taken transversely through the edging plate;

45 Fig. 3 is a detail perspective view of the edging plate; and

Fig. 4 is a similar view of the bracket arm and its locking element.

Referring to the drawings in detail, where- 50 in like characters of reference denote corresponding parts, the window casing is shown at 10, the securing plate at 11, the bracket arm at 12 and the locking element at 13.

The securing plate comprises an elongated 55 strip of metal having its longitudinal edges bent over into flanges 14, which are spaced

from the adjacent face of the plate 11 to provide longitudinal grooves 15 along each edge of the plate. This plate is adapted to be secured to the face of the window frame 60 through the medium of fastening devices 16, which are adapted to pass through the opening 17 formed in each end of the plate, the heads of these fastening devices being flush with the face of the plate. The plate 11 is 65 provided with transversely disposed spaced grooves or serrations 18, which extend throughout the length of the plate for the purpose hereinafter apparent.

The bracket arms 12 include an engaging 70 foot 19, which is disposed at an angle of substantially 90° with respect to the bracket and is adapted to enter the grooves 15 of the plate 11 for free sliding movement therein. The bracket arm 12 is provided adjacent the 75 foot 19 with oppositely extending slots 20, which are adapted to receive the flanges 14 so as to hold the bracket arm in engagement with the edging plate. The arm 12 is provided with an opening 21 for the reception 80 of one trunnion of the curtain rod, the opening shown being of elongated formation, while it is understood that the bracket upon the opposite side of the window will have a circular opening as is customary in devices 85 of this character.

Pivotaly mounted upon a trunnion 22 carried by the bracket arm 12 are spaced ears 23, the latter being located upon each side of a locking element 24. This element 24 is of substantially the same shape and configuration as the bracket arm 12, the inner end of the arm 24 however, being formed into an engaging blade 25 which is bent at an obtuse angle and provided with a sharpened edge 26 95 for engagement with the teeth or serrations 18 formed upon the edging plate 11. This plate 25 is adapted to normally engage these teeth or serrations and to be disposed at an inclination with respect to the face of the 100 plate. When in such engagement the bracket arm will be effectually locked against such movement with respect to the plate. Carried by the opposite end of the bracket arm 12 and the locking element 13 are finger pieces 105 27 and 28 respectively, the latter being aligned and having secured between them a spring 29 which normally urges the edge 26 of the plate 25 into engagement with the serrated face of the edging plate 11. When it is desired to adjust the bracket it is only necessary to move the finger pieces 27 and 28 to-

ward one another to release the blade 25 from engagement with the edging plate. This will permit of a free sliding movement of the bracket arm.

5 The invention is susceptible of various changes in its form, proportions and minor details of construction and the right is reserved to make such changes.

Having described the invention, what is 10 claimed is:—

1. A curtain fixture embodying an attaching plate, a bracket removably secured to said plate and capable of longitudinal movement thereon, a locking dog carried by the 15 bracket, said dog including a pivoted engaging plate disposed at an inclination with respect to the attaching plate and a serrated face formed on the attaching plate and engageable with the inclined plate and the lock-

ing dog to hold the bracket against movement. 20

2. A curtain fixture embodying an attaching plate, a laterally extending bracket removably secured thereto and guided upon said plate, a locking dog positioned substantially parallel to and spaced from said bracket, an angularly disposed extremity carried by one end of said dog for engagement with serrations formed on the attaching plate, spaced ears located intermediate the 30 ends of the dog for pivotal engagement with the bracket and a spring interposed between the opposite end of the dog and the bracket, whereby a pivotal movement of the dog in a direction longitudinal of the attaching 35 plate will release the bracket.

In testimony whereof I affix my signature.
CHARLES H. ANGUS.
